CLAIM

The ornamental design for a carabiner clock, as shown and described.

DESCRIPTION

FIG. 1 is a bottom perspective view of a carabiner clock showing my new design;

FIG. 2 is a front elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a back elevational view thereof; and,

FIG. 8 is an alternate front side top perspective view thereof showing the carabiner in a pivoted and open position.

The broken lines shown in the drawings are for illustrative purposes only and form no part of the claimed design.
